UNITED STATES PATENT OFFICE.

MITCHELL MACKIE, OF WAUKESHA, WISCONSIN.

INTERNAL-COMBUSTION ENGINE.

Application filed June 25, 1923. Serial No. 647,635.

This invention relates to certain new and useful improvements in attachments for internal combustion engines more especially designed for use on engines of that type employed as a motive power for vehicles.

Much difficulty is experienced in starting automotive vehicle engines under all conditions, it being necessary to close the choke or air inlet of the carburetor to thus supply the engine cylinders with raw fuel. This manner of starting the engine while apparently serving its purpose, is very injurious as but a small fraction of the raw charge drawn into the cylinders is ignited, the un-ignited fuel leaking past the pistons and diluting the lubricating oil of the crank case. Not only is this manner of starting very injurious by reason of crank case dilution, but the raw fuel floods or dampens the spark, often-times hindering more than assisting the starting operation.

The desirable manner of priming or starting an internal combustion engine is to first subject the initial or priming charge to heat sufficient to vaporize or break down the heavier particles thereof to facilitate the thorough atomizing of the charge prior to its entry into the cylinders, thus eliminating dampening of the spark and reducing crank case dilution to a minimum.

It is, therefore, an object of this invention to provide a device for reducing the initial or priming charge to a state where a thoroughly atomized combustible mixture is obtainable and spark dampening or flooding and crank case dilution are practically eliminated.

Several devices have been placed on the market seeking to provide means for heating the initial or priming charge of internal combustion engines all of which are impractical in that the energy consumed, in proportion to the effective work produced, is excessive as a result of which the battery drain is severe and an over-load often produced which is to be avoided at all times.

Having this in mind, it is another object of my invention to provide a device for heating the initial or priming charge of an internal combustion engine which is so constructed and designed as to thoroughly atomize the heavier unvaporized particles of the

fuel, whereby a minimum expenditure of energy is required to produce an efficient result.

It is another object of this invention to provide an attachment for internal combustion engines of the character described having means for supplying air to the vaporized and atomized priming charge whereby a highly combustible mixture is supplied the engine cylinders for the starting operation.

Another objectionable feature of the devices of this character now on the market is that no positive means is provided for completely disconnecting the instrument from the engine when the same is not in use, and it is, therefore, another object of this invention to provide means for instantly, completely disconnecting the instrument from the engine upon the opening of the circuit of the heating coil.

A further object of this invention resides in the provision of coordinated but independent means for instantly connecting the inlet of the attachment with the fuel supply and the outlet thereof with the engine cylinders upon connection of the heating element thereof with a source of energy, and for instantly closing the inlet and outlet upon the disconnection of the heating element from its source of energy.

And a still further object of this invention resides in the provision of an attachment for supplying a priming charge to a cylinder the outlet of which forms a complete carburetor in itself having an air inlet, a fuel supply and a venturi leading to a mixing chamber wherein the air and atomized fuel are thoroughly commingled prior to entering the engine cylinders.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention con-

structed according to the best mode I have so far devised for the practical application of the principles thereof, and in which:

Figure 1 is a side view of an initial or priming charge control or heating device embodying my invention;

Figure 2 is a similar view in longitudinal section illustrating the interior construction thereof, and

Figure 3 is an end view looking on the plane of the line 3—3 of Figure 2, the end cap member thereof being removed.

My improved device is capable of use with any design of automotive engine and in the drawing, in which like numerals designate like parts throughout the several views, 4 designates a pipe line connected with a fuel supply, not shown, and 5 an outlet pipe adapted to be connected with the cylinder or cylinders of the engine to which the device or instrument is attached preferably by being connected with the intake manifold thereof, not shown.

The line 4 is connected with one end of a cylinder or tubular casing 6 by a nipple or union 7, the inner end of which is counter-bored, as at 8, to provide a seat for a ball valve 9 which is normally spring urged to closing position by an armature or plunger 10. Cylinder 6 is preferably constructed of tubing having its ends closed by removable end plugs or caps 6'. The upper end of plunger 10 is mounted in the bore 11 of a core member 12, the lower end 13 of which is threaded in an opening in the casing diametrically opposed the inlet recess 8. The plunger 10 is constructed of iron and has a head 14 on its inner end, a spring 15 surrounding the inner end of the plunger and being confined between the end 13 of the core and said head to normally urge the ball 9 to closed position.

Core 12 is formed with an enlargement 16 adjacent its threaded end 13 to provide a shoulder abutting the wall of cylinder 6 and the inner end plate or washer 17 which, with a casing or housing 18 and an outer end plate or washer 19, encloses a coil 20 wound around the core. When energized, coil 20 draws the plunger 10 upwardly against spring 15, and with it ball 9 to free the inlet opening. The opening movement of ball 9 is adjustable by means of a set screw 21 threaded in the upper end of bore 11 and adapted to limit the upward movement of the plunger.

The head 14 is preferably of brass or other non-corrosive material to guard against a change in the adjustment of the inlet valve by the formation of corrosion on the end of the plunger, as the present day motor fuels contain considerable moisture.

The thickness of the metal of head 14 covering the end of plunger 10 is slight in

order to permit the magnetism of the plunger to lift the ball with it when the coil 20 is energized.

The end of the cylinder remote from the inlet, is provided with a pair of diametrical- 70 ly opposed openings 22 and 23 and threaded in opening 22 is the lower end 24 of a core member 25, the bore 26 of which is provided in its lower portion with a venturi 27, for the purpose hereinafter described. 75

Core 25 is formed with an enlarged portion 28 to provide a shoulder abutting the wall of the cylinder and the inner end plate or washer 29 which, with a casing 30 and an upper end plate 31, encloses and protects 80 a coil 32 wound around the core, the coil and its enclosing casing being held in position by a removable coupling or union 33, the male end 34 of which is threaded in the upper end of the bore 26 and the female 85 end of which receives the outlet 5.

The venturi 27 terminates at a point adjacent the center of the coil 32 and a web or transverse partition 35 is formed in the bore to provide a stop against which a ball 90 valve 36 is held by coil 32, when energized, against the suction created in the outlet by the engine cylinders. With the engine running, ball 36 is held in engagement with the end 34 of the coupling 35, when coil 32 is de- 95 energized, to close the outlet and disconnect the instrument and the engine intake.

Mounted in the cylinder 6 is a heating coil or resistance element 37, one end of which is grounded to the cylinder adjacent 100 the inlet, as at 38, and the other end of which is secured, as at 39, to a terminal 40 which is insulated from the casing wall by suitable material 41. One end of the coil 20 is grounded to the instrument in the conventional manner, not shown, and the other end thereof has a lead 42 electrically connected to the terminal 40. The coil 32 has one end grounded to the instrument in the conventional manner, not illustrated, and 110 its other end connected with the terminal 40 by a lead 43.

With this structure the negative side of the battery or other source of energy is grounded to the frame of the engine to which the appliance is attached and the positive side thereof is connected with a suitable control switch, not shown, from which runs a lead 44 to the terminal 40 so that upon closing of the switch the coils 20 and 32 are simultaneously energized to hold the valves 9 and 36 open and the coil 37 is heated to reduce or vaporize the fuels entering the instrument.

The fuel entering the cylinder 6 partly 125 submerges the coil 37 and that part thereof projecting above the fuel level provides disengaging surfaces from which the vaporized fuel is given off, the vaporized fuel passing outwardly from the cylinder through the 130

venturi. As the supplying of a priming charge to the cylinder of only atomized or vaporized fuel is to be avoided, it is desirable that the proper volume of air be commingled therewith. The cap 6' closing the outlet end of the cylinder has a valve controlled air inlet 45 therein of substantially L-shape controlled by a ball valve 46 operable by gravity to normally close the same, the engine suction in the casing 6 opening the valve 46 to permit the required volume of air to enter the instrument.

As the fuels on the market to-day are of very low grade, experience has illustrated that a large portion thereof will not vaporize under the degree of heat it is practical to generate in an instrument of this character and to properly dispose of these heavier particles, a jet or hollow stem member 47 is secured in the casing with its flaring or jet end 48 positioned in the venturi outwardly of its point of maximum constriction. The member 47 is secured in the casing by a screw head 49 formed on its lower end and threaded in the opening 23. The bore of the jet has an opening 50 therein whereby the heavier portions of the fuel are drawn therethrough and thoroughly atomized and commingled with the vaporized fuel and air to produce a highly combustible priming charge.

By introducing the air at the outlet end of the instrument, danger of ignition in the instrument is eliminated and preexpansion of the air is prevented, thus producing a mixture of air highly charged with vaporized and atomized fuel. The ball valve 46 traps the vapor generated in the cylinder 6 up to the time the engine, with which it is connected, starts when the suction created thereby opens the same against the force of gravity as previously described. This valve also provides a protection against the leakage from the instrument of any fuel that may accumulate in the cylinder 6 due to a leak at the valve 9.

From the foregoing description taken in connection with the accompanying drawings it will be readily obvious that I provide an instrument which, by reason of the valve controlled inlet and outlet, is absolutely disconnected from the engine when the same is inoperative; which provides the engine with a highly combustible priming charge to thus eliminate crank case dilution and spark dampening or flooding, and which, in general, facilitates the starting of the engine and, by reason of its construction, is positive of operation and substantially proof against tampering.

What I claim as my invention:

1. A device of the character described, comprising a chamber, a fuel inlet communicating with the chamber, a tubular member communicating with the chamber

and providing an outlet therefor, a magnet coil wound about said tubular member, and valve means operable by the creation of a suction in the tubular member to close the outlet, said valve means being held in open position upon energization of said magnet coil.

2. A device of the character described, comprising a chamber, a fuel inlet communicating with the chamber, a tubular member communicating with the chamber and providing an outlet therefor, a magnet coil wound about said tubular member, an outlet tube leading from the bore of said tubular member, a valve seat at the inner end of said outlet tube, and a valve member in the outlet and operable to engage the valve seat to close the outlet, said magnet coil, upon energization, holding said valve member in open position.

3. A device of the character described, comprising a chamber, a fuel inlet communicating with the chamber, a tubular member communicating with the chamber and providing an outlet therefor, a magnet coil wound about said tubular member, an outlet tube leading from the bore of said tubular member, a valve seat at the inner end of said outlet tube, and a valve member in the bore of said tubular member and adapted to be attracted toward said valve seat upon creation of a suction in the outlet tube to close the outlet, said magnet coil, upon energization, exerting a magnetic force on said valve member to hold the same out of engagement with the valve seat.

4. A device of the character described, comprising a chamber, a fuel inlet communicating with the chamber, a tubular member communicating with the chamber and providing an outlet therefor, a magnet coil wound about said tubular member, an outlet tube leading from the bore of said tubular member, a valve seat at the inner end of said outlet tube, a valve member in the bore of said tubular member and adapted to be attracted toward said valve seat upon creation of a suction in the outlet tube to close the outlet, said magnet coil, upon energization, exerting a magnetic force on said valve member to hold the same out of engagement with the valve seat, and a stop in the bore of said tubular member adjacent the center of the magnetic forces of said coil and against which said valve is held upon energization of the coil.

5. A device of the class described, comprising a chamber, a fuel inlet communicating therewith, a fuel outlet leading therefrom, a heating member disposed in said chamber and adapted to heat fuel passing therethrough, valve means for closing the inlet member, valve means for closing the outlet, and means operable upon connection of the heating member with a source of en-

ergy for holding said inlet and outlet closing means open.

6. A device of the character described, comprising a fuel chamber, a heating element mounted therein, a fuel inlet connectible with the fuel chamber, an outlet connected with said chamber, valve means normally closing said inlet, valve means operable to close said outlet upon creation of a suction therein, and means operable to simultaneously actuate the inlet and outlet valves to hold the same open.

7. A device of the character described, comprising a fuel chamber, a heating element mounted therein, a fuel inlet connectible with the fuel chamber, an outlet connected with said chamber, valve means normally closing said inlet, valve means operable to close said outlet upon creation of a suction therein, and means operable to simultaneously actuate the inlet and outlet valves to hold the same open upon connection of the heating element with a source of energy.

8. A device of the character described, comprising a chamber, a fuel supply inlet connectible with the chamber, an outlet leading from the chamber, a valve adapted to seat in the mouth of said inlet, a centrally bored core member secured to the casing with its bore communicating therewith diametrically opposite said inlet, a plunger member having its upper end slidably mounted in the bore of the core member, spring means normally urging the inner end of said plunger against the valve to cause the same to close the inlet, a magnet coil wound about the core member and adapted, upon energization, to attract the plunger upwardly and permit opening of the inlet, and readily adjustable means for limiting the movement of said plunger.

9. A device of the character described, comprising a chamber, a fuel supply inlet connectible with the chamber, an outlet leading from the chamber, a valve adapted to seat in the mouth of said inlet, a centrally bored core member having its inner end communicating with the interior of said chamber, a plunger having its upper end slidably mounted in the bore of said core, a head member mounted on the inner end of the plunger, spring means normally urging the head member against the valve to close said inlet, and means for moving the plunger against said spring to permit the movement of the valve free of the inlet.

10. A device of the character described, comprising a chamber, a fuel supply inlet connectible with the chamber, an outlet leading from the chamber, a valve adapted to seat in the mouth of said inlet, a centrally bored core member having its inner end communicating with the interior of said chamber, a plunger having its upper end

slidably mounted in the bore of said core, a head member of non-corrosive metal mounted on the inner end of the plunger and normally pressing on the valve, spring means normally urging the head member against the valve to close said inlet, means for moving the plunger against said spring to open the inlet, and means limiting the movement of the plunger against said spring.

11. A device of the character described, comprising a chamber, a fuel supply inlet connectible with the chamber, an outlet leading from the chamber, a valve adapted to seat in the mouth of said inlet, a centrally bored core member having its inner end communicating with the interior of said chamber, a plunger having its upper end slidably mounted in the bore of said core, a head member of non-corrosive metal mounted on the inner end of the plunger, spring means normally urging the head member against the valve to close said inlet, a magnet coil wound around said core member and adapted, upon energization, to attract the plunger member therein against said spring to open the inlet.

12. A device of the character described, comprising a chamber, a fuel supply inlet connectible with the chamber, an outlet leading from the chamber, a valve adapted to seat in the mouth of said inlet, a centrally bored core member having its inner end communicating with the interior of said chamber, a plunger having its upper end slidably mounted in the bore of said core, a head member of non-corrosive metal mounted on the inner end of the plunger, spring means normally urging the head member against the valve to close said inlet, and a magnet coil wound around said core member and adapted, upon energization, to attract the plunger member therein against said spring to open the inlet, said plunger being of magnetic material and being magnetized, upon energization of said coil, to attract the valve thereto and move the same therewith from the inlet.

13. A device of the character described, comprising a chamber, a fuel inlet connectible with the chamber, an outlet leading therefrom, means for heating fuel in said chamber, the fuel particles vaporized by said heating means passing outwardly through the outlet, and a tubular stem member having an opening communicating with the liquid fuel in the container and its upper outlet end disposed in said outlet whereby the heavier unvaporized particles of fuel are drawn into the outlet and atomized.

14. A device of the character described, comprising a chamber, a fuel inlet connectible with the chamber, an outlet leading therefrom, means for heating fuel in said chamber, the fuel particles vaporized by said heating means passing outwardly

- through the outlet, a tubular stem member having an opening communicating with the liquid fuel in the container and its upper outlet end disposed in said outlet whereby 5 the heavier unvaporized particles of fuel are drawn into the outlet and atomized, and means for supplying air to the chamber to be commingled with the vaporized and atomized fuel.
- 10 15. A device of the character described, comprising a chamber, a fuel inlet connectible with the chamber, an outlet leading therefrom, a venturi in said outlet, a tubular stem extended into said outlet with its 15 outer end positioned in the venturi adjacent the point of maximum constriction and its inner end communicating with the fuel in said chamber, and means for reducing the lighter particles of fuel into vapor, said 20 vaporized fuel entering the venturi around said tubular stem and the heavier particles of fuel being drawn through the tubular stem and commingling with the vaporized fuel.
- 25 16. A device of the character described, comprising a chamber, a fuel inlet connectible with the chamber, an outlet leading therefrom, a venturi in said outlet, a tubular stem extended into said outlet with its 30 outer end positioned in the venturi adjacent the point of maximum constriction and its inner end communicating with the fuel in said chamber, means for reducing the lighter particles of fuel into vapor, said vaporized 35 fuel entering the venturi around said tubular stem and the heavier particles of fuel being drawn through the tubular stem and commingling with the vaporized fuel, and means adjacent said outlet for supplying 40 air to the mixture.
- 45 17. A device of the character described, comprising a chamber, a fuel inlet connectible with the chamber, an outlet leading therefrom, a venturi in said outlet, a tubular stem extended into said outlet with its 50 outer end positioned in the venturi adjacent the point of maximum constriction and its inner end communicating with the fuel in said chamber, means for reducing the lighter 55 particles of fuel into vapor, said vaporized fuel entering the venturi around said tubular stem and the heavier particles of fuel being drawn through the tubular stem and commingling with the vaporized fuel, means 60 adjacent said outlet for supplying air to the mixture, and means operable to close said outlet.
- 65 18. An appliance of the character described, comprising a chamber, means for supplying fuel to the chamber and includ- 65 ing an inlet, an outlet leading from the chamber, a valve seat in the outlet, a free floating valve in the outlet and normally held by gravity in a position free of the outlet, suction on the outlet drawing the valve
- to engagement with the seat and continued suction holding the same in outlet closing position, and magnetic means operable to secure the valve in its normal position against the influence of suction at the outlet. 70
- 75 19. An appliance of the character described, comprising a chamber, means for supplying fuel to the chamber, an outlet leading from the chamber and including a tubular core, a valve seat adjacent the outer end portion of the core, a valve member of magnetic material free within the bore of the core, a stop in said core bore below the valve seat and against which the valve member normally rests, the valve member being drawn from the stop to engagement with said seat to close the outlet upon the creation of a suction in the outlet, and magnetic means operable to attract the valve member 80 and hold the same in engagement with the stop against the closing effects of suction created in the outlet. 85
- 90 20. A device of the character described, comprising a fuel chamber, means for supplying fuel to the chamber, means located wholly within for vaporizing the lighter particles of the fuel, means for atomizing the heavier particles of the fuel, and an outlet leading from the chamber and through which the vaporized and atomized 95 portions of fuel pass. 95
- 100 21. A device of the character described, comprising a fuel chamber, means for supplying fuel to the chamber, means located wholly within for vaporizing the lighter particles of the fuel, means for atomizing the heavier particles of the fuel, an outlet leading from the chamber and through which the vaporized and atomized 105 portions of fuel pass, and means located adjacent the outlet end of said chamber for supplying air to the vaporized and atomized particles of fuel to form a combustible mixture. 105
- 110 22. A device of the character described, comprising a fuel chamber, means for supplying fuel to the chamber, means for vaporizing the lighter particles of the fuel, means for atomizing the heavier particles of the fuel, an outlet leading from the chamber and through which the vaporized and atomized 115 portions of fuel pass, means located adjacent the outlet end of said chamber for supplying air to the vaporized and atomized particles of fuel to form a combustible mixture, and a venturi in the outlet for effecting the thorough commingling of the particles of fuel and the air. 120
- 125 23. A device of the character described, comprising an elongated substantially horizontal chamber, means positioned at one end of the chamber for supplying fuel thereto, an outlet leading from the other end of the chamber, heating means positioned with the chamber medially of the inlet and outlet, said 130

heating means vaporizing the lighter particles of fuel and said vaporized particles passing freely from the chamber through the outlet, and means for atomizing the heavy particles of fuel and discharging the atomized particles into the outlet to be commingled with the vaporized particles.

24. A device of the character described, comprising an elongated substantially horizontal chamber, means positioned at one end of the chamber for supplying fuel thereto, an outlet leading from the other end of the chamber, heating means positioned with the chamber medially of the inlet and outlet, said heating means vaporizing the lighter particles of fuel and said vaporized particles passing freely from the chamber through the outlet, means for atomizing the heavy particles of fuel and discharging the atomized particles into the outlet to be commingled with the vaporized particles, and means for introducing the air to commingle with the vaporized and atomized particles of fuel.

25. A device of the character described, comprising a chamber, a fuel supply inlet engageable with the chamber, an outlet leading from the chamber, a floating valve member adapted to seat in the mouth of the out-

let, a magnetic plunger forming an armature, means urging the plunger to normally engage the floating valve and yieldably secure the same in position closing the mouth of said inlet, and a magnetic coil adapted upon energization to free the armature of said valve member, said plunger being magnetized by energization of the coil and attracting the valve thereto to move the same with it to a position free of the inlet.

26. A device of the character described, comprising a chamber, a fuel supply inlet engageable with the chamber, an outlet leading from the chamber, a floating valve member adapted to seat in the mouth of the outlet, a magnetic plunger forming an armature, a tip of non-magnetic material secured on the end of the plunger and engageable with the valve member, means yieldably urging the plunger against the valve member, and a magnetic coil adapted upon energization to free the armature of said valve member, said plunger being magnetized by energization of the coil and attracting the valve thereto to move the same with it to a position free of the inlet.

In testimony whereof I affix my signature.
MITCHELL MACKIE.
